UNITED STATES PATENT OFFICE.

SERAFINO GALLI, OF BREEZY HILL, KANSAS.

CAR-LOCK FOR MINE-ELEVATORS.

1,268,001.

Specification of Letters Patent.

Patented May 28, 1918.

Application filed January 4, 1918. Serial No. 210,305.

To all whom it may concern:

Be it known that I, SERAFINO GALLI, a citizen of the United States, residing at Breezy Hill, in the county of Crawford and State of Kansas, have invented certain new and useful Improvements in Car-Locks for Mine-Elevators; and I do declare the following to be a full, clear, and exact description of the invention, such as will enable 10 others skilled in the art to which it appertains to make and use the same.

One object of my invention is to provide a locking means for mine car elevators which will effectively secure the cars on the elevator while the latter is moving upwardly or downwardly, the arrangement being such that as a car passes onto the elevator, it releases the locking means so that the latter is automatically applied to hold the car.

20 A further object is to provide novel construction whereby the passage of one car from the elevator and another onto the same is necessary before the lock will be applied.

A still further object is to provide a pair 25 of dogs operated automatically by projection of the locking block, said dogs gripping the axles of the car to hold them against possible shifting.

With the foregoing general objects in view, the invention resides in the novel features of construction and unique combinations of parts to be hereinafter fully described and claimed, the descriptive matter being supplemented by the accompanying 35 drawings which form a part of this specification and in which:—

Figure 1 is a top plan view of a mine elevator equipped with the invention;

Fig. 2 is a side elevation;

40 Fig. 3 is a central longitudinal section on the plane of the line 3—3 of Fig. 1, showing the locking block projected between the car axles and the axle gripping dogs in operative position;

45 Fig. 4 is a vertical transverse section on the plane of the line 4—4 of Fig. 3 showing the relative positions of parts when the lock is in operative position;

50 Fig. 5 is a detail section similar to a portion of Fig. 4 and illustrating the relative positions of parts when the lock has been released to permit the car to leave the elevator;

55 Fig. 6 is a view similar to Fig. 5 illustrating the relations of parts when the car

traveling from the elevator depresses the operating plunger;

Fig. 7 illustrates the positions of parts when the plunger ascends from the position of Fig. 6;

60 Fig. 8 is a detail section illustrating the result of a second depression of the operating plunger by another car passing onto the elevator;

Fig. 9 is a horizontal section on the plane 65 of the line 9—9 of Fig. 7;

Fig. 10 is a vertical section on the plane indicated by the line 10—10 of Fig. 7;

Fig. 11 is a perspective view of the guide for the locking block; and

70 Fig. 12 is a perspective view of said block.

In the drawings above briefly described, the numeral 1 designates a mine car elevator consisting of an upper section 2 carrying the rails 3, a lower section 4, and a suitable 75 supporting structure 5 hinged at 6 to the base section 4 for supporting the track carrying section 2 therefrom, the hinge being located adjacent one end of the elevator and the other end of the latter being held against 80 depression by suitable posts or the like 7; The section 2 may be tilted around its hinges 6 to cause a car to travel from the rails 3 as will be readily understood.

85 Mounted on the upper section 2 of the elevator 1 and positioned between the rails 3, is a bar 8 having a thickened central portion formed with a recess 9 opening through the upper and lower edges and through one side of said bar, the open side of said recess being closed however by a plate 10 so that 90 a truly rectangular shape is imparted to the recess 9 for effectively guiding a rectangular lock block 11 which is received therein for projection between the car axles A. Re-

95 cesses 12 are formed in the end walls of recess 9 and a pair of hook-like axle gripping dogs 13 are pivoted in said recesses 12 as shown clearly in Fig. 3, said dogs being automatically moved to operative position 100 by ascent of the lock block 11. This block is provided with recesses 14 in its ends into which the dogs 13 drop when said block is lowered, whereby to permit the car to travel from the elevator.

105 A link 15 depends from the center of the lock block 11 and at its lower end is provided with an arched fork 16 in which a dog 17 is pivoted, said dog normally underlying one end of a release lever 18 so that opera-

tion of this lever will pull downwardly upon the fork 16 and the link 15 to lower the lock block 11 against the tension of a coiled spring 19 which holds said block in raised 5 position. As shown clearly in Fig. 3, the relation of the dog 17 and lever 18 is such as to permit tilting of the upper elevator section 2 without offering any obstruction whatever to such movement.

10 For holding the lock block 11 in lowered position, a sliding latch bolt 20 is provided, one end of said bolt extending through one side of the vertical guide 21 in which the fork 16 operates as will be clear from Figs. 4 to 7. The other end of the bolt 20 is spaced below one of the rails 3 and provided with a longitudinal slot 22, a suitable bearing 23 being provided for slidably supporting the central portion of the bolt. Between 15 bearing 23 and a shoulder 24 on the bolt 20, a coiled spring 25 is provided for projecting said bolt whenever lever 18 is operated to lower the fork 16 to the extent depicted in Figs. 5, 6 and 7. When the bolt is thus projected, the outer end of the slot 22 is positioned below the beveled lower end 26 of a vertically moving operation plunger 27 which projects upwardly through the rail 3 above mentioned (see Fig. 5). When the 20 car now travels from the elevator, one of its wheels W will depress the plunger 27 so that its beveled end 26 engages the outer end of slot 22 and partially withdraws the bolt 20 against the tension of spring 25 as 25 depicted in Fig. 6. The tension of spring 19 is greater than that of the spring 25, so that the bolt will remain in its partially retracted position, due to friction. When now a second car passes onto the elevator, 30 one wheel thereof will again depress the plunger 7, and in order that such depression may totally release the bolt 20 to permit spring 19 to automatically move the lock block 11 to operative position, I provide the 35 following construction.

A slide 30 is mounted on the outer end of bolt 20 and is formed with a longitudinal slot 31 which is disposed over the slot 22, the inner end of said slide being connected 40 to the bolt by a rivet or the like 32 which passes through said slot, said slide being normally forced outwardly by the coiled spring 33. Upon the first depression of the plunger 27 as above set forth, the slide 30 45 will move away from the outer end of slot 22 as depicted in Fig. 6, but when the plunger 27 again rises, the spring 33 will return the slide to its initial position, thus disposing its outer end beneath the bevel 26 of plunger 27 as shown in Fig. 7. As the next 50 car passing onto the elevator now depresses this plunger, its beveled end will engage the slide 30 as shown in Fig. 8 so that the bolt 20 will be totally withdrawn to permit 55 spring 19 to move the block 11 to operative

position between the axles A, the dogs 13 being automatically projected at the same time.

From the foregoing, taken in connection with the accompanying drawings, it will be 70 obvious that although my invention is of simple and inexpensive nature, it will be highly efficient and durable for the purposes intended. The operation is the same at both the upper and lower ends of the mine 75 shaft, that is the lever 18 is operated to release the lock block 11, thus permitting the car on the elevator to travel therefrom. At the same time the bolt 20 is automatically applied to hold the lock block in lowered 80 position. The car in passing from the elevator depresses the plunger 27 and thus partially withdraws the bolt 20. As the next car now travels onto the elevator, the plunger 85 is depressed for a second time and by its engagement with the slide 30, the bolt 20 is totally withdrawn so that the spring 19 moves the lock block to operative position and applies the dogs 13. The lever 18 may either be actuated by hand or by any suitable type of trip mechanism.

Since probably the best results are obtained from the several specific details shown and described, these details are preferably employed, but I wish it understood 95 that within the scope of the invention as claimed, numerous minor changes may well be made.

I claim:

1. In a car lock for elevators, the combination of a car elevator, a lock for holding the car on said elevator, means for releasing said lock, a latch for holding said lock in released position, a car-depressed operating member for partially releasing 100 said latch when the car leaves the elevator, means including said operating member for completely releasing said latch when another car passes onto said elevator, and means for moving said lock to operative position when said latch is released.

2. In a car lock for elevators, the combination of a car elevator, a lock for holding the car on said elevator, means for releasing said lock, a latch for holding said lock in released position, a car-depressed operating member having a cam surface, an abutment on said latch coacting with said cam surface on depression of said member by a car leaving the elevator, whereby to 115 partially release the latch, an additional abutment on said latch for engagement with said cam surface when said operating member is again depressed by passage of another car onto the elevator, whereby to completely 120 release said latch, and means for moving said lock to operative position when said latch is released.

3. A structure as specified in claim 2, said additional abutment being movable away 125

from said first named abutment upon the first mentioned depression of said operating member, and a spring for returning said additional abutment after ascent of said operating member.

4. In a car lock for elevators, the combination of a car elevator, a lock for holding a car on said elevator, means for releasing said lock, a horizontally slidable latch bolt for holding said lock in released position, said bolt having a longitudinal slot, a car-depressed plunger whose lower end is positioned above one end of said slot and beveled to engage said end, whereby to partially withdraw said bolt upon depression of said plunger by passage of the car from the elevator, a plate mounted on said bolt and having a slot whose end is disposed for engagement by said beveled end of said plunger when the latter is depressed by passage of a second car onto the elevator, whereby to totally release said bolt, said plate being slidable away from said end of the slot in said bolt upon said first named depression of said plunger, means for returning said plate upon ascent of said plun-

ger, and means for moving said lock to operative position when said bolt is released.

5. In a car lock for elevators, the combination of a car elevator, a vertically slideable lock block of a length to abut both axles of the car, means for raising said block between the car axles, a fixed guide for said block, a pair of axle-gripping dogs mounted pivotally on said guide at the ends of said block and moved to operative position by ascent of said lock block, and means for lowering said block.

6. In a car lock for elevators, the combination of a car elevator, a lock block and means for raising said block between the car axles, a guide for said block, a pair of axle-gripping dogs mounted at the ends of said guide and moved to operative position by the ascent of said lock block, and means for lowering said block, the ends of said block having recesses into which said dogs drop when the block is lowered.

In testimony whereof I have hereunto set my hand.

SERAFINO GALLI.
